UNITED STATES PATENT OFFICE.

ELIHU THOMSON, OF SWAMPSCOTT, ASSIGNOR TO THE THOMSON-HOUSTON ELECTRIC COMPANY, OF BOSTON, MASSACHUSETTS.

POLE-PIECE FOR DYNAMO-ELECTRIC MACHINES.

SPECIFICATION forming part of Letters Patent No. 498,327, dated May 30, 1893.

Application filed August 26, 1892. Serial No. 444,240. (No model.)

To all whom it may concern:

Be it known that I, ELIHU THOMSON, a citizen of the United States, residing at Swampscott, county of Essex, State of Massachusetts, have invented certain new and useful Improvements in the Manufacture of Dynamo-Electric Machines, of which the following is a specification.

The present invention relates to means for dividing the projecting poles or pole faces of dynamo electric machines or motors, particularly of alternating current dynamos in which by the action of the armature, eddy currents may be set up which waste power in the pole faces. The construction is more particularly adapted to such armatures as are provided with projections of iron running near to the pole faces, or provided with a discontinuous exterior of iron. It has been customary to construct pole faces of laminæ or laminated iron in such cases. Inasmuch, however, as the actions which are to be guarded against are not, in many cases, so important as to demand an entirely laminated structure, and inasmuch further, as the disturbing actions do not extend back into the pole face to any great extent in many cases, my present invention is a cheap means for obtaining a saving of power depending upon slotting of the pole faces, which is sometimes done by mechanical cutting appliances. In my invention during the process of forming the pole pieces from either cast or wrought iron I produce the slots by proper molding. The preferred mode of producing the slots is shown in the accompanying drawings.

Figure 1 represents a piece of the pole, in the face of which are inserted heat resisting pieces of non-conducting material. Fig. 2 is an end view of the same. Figs. 3 and 4 show slot-forming pieces of sheet metal. Figs. 5 and 6 are vertical and horizontal sections respectively of a molding flask for casting pole-pieces. Fig. 7 shows a pole piece slotted, and Fig. 8 a portion of an alternating dynamo field magnet with slotted pole pieces.

The divisions in the pole piece A may be open slots *a*, as shown in Figs. 3 and 7; or the slots may be filled with an insulating mate-

rial B as in Figs. 1 and 4. In Fig. 7 the slots 50 are cored out by inserting suitable cores in the mold C before casting. Or, the cores may consist of slabs of heat-resisting, non-conducting material B, such as baked clay, and the pole piece when cast, will retain these 55 pieces in it, as shown in Fig. 1.

I find that one of the best means of introducing the insulating substance for producing slots in the poles is by taking a piece D of sheet iron and bending it into a **U** form, 60 as in Fig. 3, so as to leave a little space between the two sides, inserting this into the mold and casting around it, in which case the metal fits itself and welds itself to the piece of sheet iron which then becomes practically 65 a part of the structure, and may be machined or cut as is the other part. Where the temperature is so low as not to cause a welding, the pieces may be knocked out afterward, but in either case they form the slot required. 70

It is preferable in some cases to introduce between the folded piece of metal a slab or sheet of insulating material B, which may be asbestos or clay, or a loose slab of any such substance. The piece D in Fig. 4 is introduced into the flask or mold as in Figs. 5 and 6.

What I claim as new, and desire to secure by Letters Patent, is—

1. A cast metal pole piece for a dynamo, 80 having in its face a number of slots, each containing an insulating piece of heat resisting material, substantially as described.

2. A cast metal pole piece for a dynamo, 85 having in its face a number of **U**-shaped pieces of sheet metal, substantially as described.

3. A cast metal pole piece for a dynamo, 90 having embedded in its face a number of **U**-shaped pieces of sheet metal, each having a slab of insulating material infolded in it, substantially as described.

In witness whereof I have hereunto set my hand this 22d day of August, 1892.

ELIHU THOMSON.
